UNITED STATES PATENT OFFICE.

AUGUST DLOUHY, OF WALLINGFORD, CONNECTICUT, ASSIGNOR TO H. L. JUDD COMPANY, INC., OF WALLINGFORD, CONNECTICUT, A CORPORATION OF DELAWARE.

DESIGN FOR A DRAPERY-POLE RING.

Application filed May 2, 1928. Serial No. 28,536. Term of patent 3½ years.

To all whom it may concern:

Be it known that I, AUGUST DLOUHY, a citizen of the United States, residing at Wallingford, in the county of New Haven and State of Connecticut, have invented a new, original, and ornamental Design for a Drapery-Pole Ring, of which the following is a specification, reference being had to the accompanying drawing, forming part thereof.

Fig. 1 is a front elevation of a drapery pole ring, showing my new design.

Fig. 2 is a top plan view of the article shown in Fig. 1.

I claim:

The ornamental design for a drapery pole ring, as shown.

AUGUST DLOUHY.
